UNITED STATES PATENT OFFICE.

HARRY A. GOLD, OF BROOKLYN, NEW YORK.

CAP.

Application filed September 20, 1927. Serial No. 220,648.

This invention relates to caps and particularly to a combination cap, muffler, and forehead protector; one of its objects being the provision of a head gear which may be 5 conveniently and cheaply assembled.

Another object of my invention is the provision of a cap comprising a separate forehead protector which is stitched at spaced intervals to the crown of the cap.

10 A further object of my invention is the provision of a cap having a non-extensible band secured to the edge of the crown portion thereof below the edge portion of a separate forehead protector for permitting 15 stretching of the forehead protector while preventing stretching of the edge portion of the crown to afford a tight fitting relation between the edge portions of the crown and forehead protector when the cap is stretched 20 on the head of a wearer.

Other objects will appear hereinafter, the novel features and combinations being more clearly set forth in the appended claims.

In the drawings:

25 Fig. 1 is a fragmentary elevational view of a strip of material from which my improved cap is constructed showing the outer surface thereof.

30 Fig. 2 is a fragmentary elevational view of a strip of material from which my improved cap is constructed showing the inner surface thereof.

35 Fig. 3 is a perspective view of the material disclosed in Figs. 1 and 2 showing the same formed in the shape of a crown of a cap.

Fig. 4 is a fragmentary of a band embodied in my improved cap.

40 Fig. 5 is a perspective view of a crown portion of my improved cap illustrating the band thereon.

Fig. 6 is a plan view of the muffler section of my improved cap.

45 Fig. 7 is a plan view of a forehead protector embodied in my invention.

Fig. 8 is a perspective view of a completed cap embodying my invention showing the muffler in downwardly folded position.

50 Fig. 9 is a sectional view taken on the line 9—9 of Fig. 8.

Fig. 10 is a perspective view of a completed cap embodying my invention illustrating the muffler portion in upwardly 55 folded position.

Referring particularly to the drawings

the numeral 10 designates a section of material of full cardigan knit and the numeral 11 designates an integral section of purled stitches, the section 11 being of closer knit than the section 10. The outer surface of the sections 10 and 11, as shown in Fig. 1 are allowed to remain as formed by the knitting operation and the inner surfaces of the sections are brushed for providing a nap or Angora finish. As illustrated in Figs. 3 and 5 the integral strips of material are formed in the shape of the sides of a bowl and the extremities are stitched together as at 12.

A band comprising a tubular knitted member 13 is positioned at the front of the lower edge of the sides of the crown portion and is secured to the edge portion by stitches 14 which extend completely around the entire circumference thereof. It should be understood that the material of the tubular member 13 is so constructed as to resist stretching and that its presence at the front portion of the cap prevents stretching thereof and causes the front portion to firmly engage the forehead of a wearer at the edge portions for preventing wind, snow, or rain from gaining entrance therebelow, or thru the material of the front portion of the cap. Attention is directed that a wearer's forehead needs the most protection, since the remainder portion of a wearer's head covered by the cap is normally provided with hair. Quite obviously, if the front portion of the cap cannot stretch, the pores in this portion will not be enlarged as the cap is forced upon the wearer's head.

The muffler section 15 illustrated in Fig. 6 comprises a curved upper edge 16 which, positioned at its intermediate portion adjacent the back portion of the lower edge of the sides of the crown, is secured at its intermediate portion to the back portion of the edge of the crown by the stitches 14 which extend around the circumference of the crown as above described.

As illustrated in Fig. 8, a forehead protector 17 is stitched at its upper edge 18 to the front of the side portion of the crown by stitches 19. The lower edge 20 of the protector 17 is stitched at spaced intervals as 21, 22, and 23 to the lower edge of the crown and the lower edge of the band 13. It should be understood that the edge 20 of the protector is not secured to the crown throughout its entire length but that the edges of the two members are unattached

as shown in Fig. 8 between the stitched portions 21, 22, and 23. This arrangement prevents the accumulation of lint and dust between the edge portions of the crown and 5 protector portion and permits convenient access to the compartment therebetween for cleaning purposes. It should be understood that the extremities of the band 13 are within the extremities of the protector 17 and 10 that the end portions of the lower edge are secured directly to that portion of the edge of the cap beyond the extremities of the band 13 indicated by numerals 24 and 25 in Fig. 8. This arrangement causes a greater 15 degree of expansion to exist throughout the protector than exists throughout that portion of the crown which is stitched to the band 13 and as a result the lower edge portions of the protector are pulled firmly 20 against the band and the crown portions designated by numerals 24 and 25 and a light fitting relation to exist between the lower edge 20 of the protector and the edge of the crown.

25 Buttons 26 and 27 are sewed to protector 17 and are adapted to engage in buttonholes 28 and 29, respectively, of the muffler section 15 when the latter is folded upwardly as viewed in Fig. 10. It should be understood 30 that a button 30 is secured to the outer side of one end portion of the muffler section 15 for receiving the buttonhole of the other end of the muffler section when the latter is folded downwardly and disposed around the 35 neck and below the chin of a wearer.

It should be understood also that the upper section 11 comprising purled stitches is formed to provide a spherically shaped top crown portion as illustrated in Figs. 8 and 40 9; the corners of the top portion of the sec-

tion 11 being cut off and the edges abutted against each other and sewed by continued stitches in line with the stitches 12. It should also be understood that the row of 45 stitches 12 extends over the top of the crown from the lower rear edge portion to the lower front edge portion as shown in Fig. 10.

Obviously those skilled in the art may 50 make various changes in the details and arrangement of parts of my invention without departing from the spirit and scope thereof.

Having thus described my invention on 55 what I claim as new and desire to secure by United States Letters Patent is:

1. A cap of the class described, comprising a crown portion of stretchable material, a forehead protector of stretchable material secured thereto, and a means for preventing that portion of the crown beneath the forehead protector from stretching, without resisting stretching of the remaining portion of the crown, for the purpose described. 60

2. A cap of the class described, comprising a crown portion of stretchable material, a forehead protector of stretchable material secured thereto, and a means for preventing that portion of the crown beneath the forehead protector from stretching, without resisting stretching of the remaining portion of the crown, for the purpose described, said means consisting of a non-stretchable band secured to the bottom edge of the crown, 70 only at the portion beneath the forehead protector. 75

In testimony whereof I have affixed my signature.

HARRY A. GOLD.
